UNITED STATES PATENT OFFICE.

JAMES F. SNOW, OF PAWTUCKET, RHODE ISLAND.

TROLLEY-ARM FOR ELECTRIC CARS.

SPECIFICATION forming part of Letters Patent No. 681,891, dated September 3, 1901.

Application filed February 19, 1901. Serial No. 47,925. (No model.)

To all whom it may concern:

Be it known that I, JAMES F. SNOW, a citizen of the United States, and a resident of Pawtucket, in the county of Providence and 5 State of Rhode Island, have invented a new and useful Improvement in Trolley-Arms for Electric Cars, of which the following is a specification.

This invention has reference to an improvement in that class of devices by which the trolley or contact-roller used on electrically-propelled cars is supported and operated to connect the electric motor with the overhead conductor of electric energy.

15 It has been found in practice that the flanges of trolley-wheels wear out rapidly, because the groove between the flanges of the wheel in passing over curves does not follow the curve of the conductor-wire. The flanges 20 grind on the conductor-wire and wear both the flanges and the wire. It has been suggested to support the trolley-wheel in a fork pivoted in the end of the trolley-arm; but such a wheel depends for guidance on the contact 25 of the flanges with the conductor-wire and does not prevent the wear of the trolley-wheel and the conductor-wire.

The objects of this invention are to reduce the wear on the trolley-wheel and the conductor-wire and secure a more reliable contact.

The invention consists in the peculiar and novel construction whereby the trolley-wheel is guided in its passage over curves and adjusts itself to vertical changes in the conductor-wire, as will be more fully set forth hereinafter.

Figure 1 is a side view of part of a trolley-arm provided with my improved trolley-wheel support. Fig. 2 is a transverse view, partly in section, of the auxiliary spring connection. Fig. 3 is a vertical sectional view of the swivelled fork forming the rocking support of the wheel-arm.

45 Similar marks of reference indicate corresponding parts in all the figures.

In the drawings, A indicates the usual trolley-arm, which is connected with the car at its lower end in the usual manner, a a bracket secured to the end of the trolley-arm A, and a' a socket in which the spindle a² of the fork a³ is pivotally supported. The spindle a² is

provided with an annular groove, into which a pin, in screw-thread engagement with the wall of the socket, enters to secure the spindle and fork in position, as shown in Fig. 3. The lever B is pivotally supported in the fork a³. In the preferred form, as shown in Fig. 1, the lever B has the sleeve b, which is pivoted in the fork a³ and forms the supports of the arms b' and b², projecting at different angles from the sleeve. The trolley-wheel c is journaled in the fork c' at the end of the arm b'. The sleeve b³ on the arm b² of the lever B is connected with the sleeve b⁴ on the trolley-arm A by the coiled spring b⁵. The sleeve b³ is also connected by means of the coiled spring b⁶ with the loop b⁷. To the opposite or lower end of the loop b⁷ the cord b⁸ is secured, by which the trolley-arm is controlled.

In an electrically-controlled car the trolley-arm practically maintains its position on a line with the center of the car. In turning a curve the car and trolley-arm follow the curve; but the free end of the trolley-arm and the trolley-wheel journaled in this end move when unrestrained by the conductor-wire through a curve of much greater radius than the curve of the track or the conductor-wire. To permit the trolley-wheel to more readily follow the conductor or trolley wire, the lever B is pivotally supported in the fork a³, which can turn in the socket a'. The trolley-wheel c is journaled in the rear end of the lever B, beyond the pivotal support of the lever in the socket. The arm b² of the lever B controls the lateral movement of the lever, the spring b⁵ drawing the end of the lever B toward the trolley-arm A and the trolley-wheel against the trolley-wire. The vertical rocking movement of the lever B is limited by the loop b⁷, and when passing through tunnels, bridges, or other places where the conductor or trolley wire is lower than normally the spring b⁶ acts to maintain the contact of the trolley-wheel with the conductor or trolley wire. By this construction the lever B acts as a leader for the trolley-wheel, having vertical and lateral movement independent of the movement of the main trolley-arm. The arm b' of the lever B may be of such length as will place the socket a' in the best position to lead the trolley over the curves of the conductor-wire.

Having thus described my invention, I

claim as new and desire to secure by Letters Patent—

1. A trolley-arm for electric cars having a lever pivotally secured in a fork the vertical 5 spindle of which is supported in a socket of the main trolley-arm, the movement of the lever being restricted by springs, as described.
2. A trolley-arm for electric cars having a socket near its free end, in combination with 10 a fork supported in the socket, a lever pivoted in the fork, a trolley-wheel on one end of the lever, and a coiled spring connecting the other end of the lever with the trolley-arm, as described.
- 15 3. In a trolley-arm for electric cars, the combination with the main trolley-arm and a

socket on the same, of a lever, a trolley-wheel on the end of the lever extending beyond the socket, a coiled spring connecting the opposite end of the lever with the trolley-arm, a 20 pivotal support for the lever journaled in the socket, a loop extending around the main trolley-arm and a coiled spring connected with the loop and the pivoted lever, as described.

In testimony whereof I have signed my name to this specification in the presence of two subscribing witnesses.

JAMES F. SNOW.
